RUFFLING MECHANISM FOR SEWING MACHINES

Frank A. Kucera, Chicago, Ill., assignor to Union Special Machine Company, Chicago, Ill., a corporation of Illinois

Application January 18, 1935, Serial No. 2,345

7 Claims. (Cl. 112—132)

This invention relates to ruffling mechanisms for sewing machines; and provides a simple and reliable mechanism of the kind referred to, of which the parts are concealed and protected as far as possible within the housing or frame of the machine, and which is capable of regulation from the exterior so that tucks or ruffles of different sizes can be made.

It is a further aim of my invention to render the adjustment of such mechanism easy and quick of accomplishment, and to permit repeated re-settings of the mechanism to be made with predetermination of fabric tucks of different sizes.

Another object of my invention is to provide means whereby the mechanism may be adjusted for operation upon fabrics of different degrees of stiffness.

Still other objects and attendant advantages of this invention will be manifest from the detailed description which follows.

Fig. I of the drawings shows, in side elevation, a sewing machine fitted with a ruffling mechanism conveniently embodying the present improvements, a portion of the machine frame being broken out and in section to expose important interior details.

Fig. II is a front elevation of the machine.

Fig. III is a fragmentary detail sectional view taken as indicated by the arrows III—III in Fig. I and drawn to a larger scale.

Fig. IV is a view corresponding to Fig. III with the parts in a different position of adjustment; and

Fig. V is a detail sectional view taken as indicated by the arrows V—V in Fig. IV.

The machine herein illustrated comprises a hollow base or work table 1 with a standard and an overhanging gooseneck 2, which, at its free end, terminates in a head 3 providing guidance for a vertically reciprocating bar 4 for the sewing needle 5. Through suitable connections, not illustrated, the bar 4 is actuated from the main shaft of the machine which is indicated at 6 in Figs. I, II and III. Also guided in the head 3 is a vertical bar 7 to the lower end of which is secured a presser foot 8, said bar being subject to a spring (not shown) by which the presser foot is yieldingly held in engagement with the top of the work table 1 of the machine.

As illustrated, the presser foot 8 has an independently movable component 9 which is pivoted at 10 and yieldingly urged downward toward the work table by a light spring 11, the outer end of said component being upwardly inclined as at 12.

Incident to the operation of the machine two strips of fabric are fed in superimposition to the needle 5—a ground strip through a folder 13, and a strip which is to be ruffled through a folder 14. These folders 13 and 14 are convergent toward the needle 5, and interposed between them is a separator plate 15 which terminates at the presser foot 8, see Fig. II. The lower folder 13, it will be observed, is supported by a bracket 16 secured to the base 1 of the machine; while the upper folder 14 and the separator plate 15 are supported by a bracket member 17 secured to the head 3 of the overhanging arm 2 of the machine.

The ruffling mechanism with which the present invention is more particularly concerned comprises a shaft 18, which, as shown in Fig. I, extends horizontally along one side of the gooseneck 2 of the machine, and which has journal support in spaced bearings 19 rigidly secured to said gooseneck by means of screws 20 by which perfect alignment is obtained. Affixed to the front end of the rock shaft 18 is a pendant arm 21 whereto is pivotally attached at the swinging end, a member 22 carrying a ruffler blade 23. The member 22 is subject to a tension spring 25, which, at the top, engages an anchorage lug 26 clamped, by means of a screw 27, to the arm 21. From Fig. II it will be seen that the spring 25 serves to hold the front edge of the ruffler blade 23 yieldingly in contact with the separator plate 15 hereinbefore referred to. The pressure of the ruffler blade 23 toward the plate 15 can be varied by regulating the tension of the spring 25 through pivotal adjustment of the anchorage lug 26 about its securing screw 27.

Rocking movement is imparted to the shaft 18 through means which includes an eccentric 28 on the main shaft 6 of the machine. The rod 29 of this eccentric 28 extends upward within the hollow of the vertical portion 2a of the gooseneck 2, and is pivotally connected at its upper end to one end of an arcuate arm 31. As shown in Figs. III—V, the arcuate arm 31 is of dovetail cross sectional configuration, and has its center of curvature in the axis of the eccentric 28 when said arm is at the end of its upward swing with the ruffler blade 23 in its fully advanced position at the needle 5 of the machine. As shown in Figs. III—V, the arcuate arm 31 is slidably engaged in the correspondingly configured slot 32a of a head 32 secured to the rear end of the rock shaft 18, said slot extending crosswise of the axis of said shaft. An axially hollow clamp sleeve 33 loose on a screw stud projecting laterally from the head 32

32, has a beveled surface 33a to engage the lower bevel of the arm 31. By means of a winged nut 35 engaging threads on the outer end of the stud 34, the sleeve 33 is forced inwardly and thereby 5 operates as a wedge to securely clamp the arcuate arm 31 in the head 32. Upon loosening the wing nut 35, the arcuate arm 31 may be set in different positions in the slot 32a of the head 32 for the purposes of varying the extent of the movement 10 imparted to the ruffler blade 23. In order to facilitate such adjustments, the arcuate arm 31 is provided with graduations 36 for selective registry with an arrow mark 37 on the head 32. A pair of spaced, laterally projecting pins 38 and 39 15 on the arcuate arm 31 serve, by cooperation with the head 32, to limit the extent to which said arm can be shifted with respect to said head. The outer end of the arcuate arm 31 is gouged at 40 for ease of grasping it in making the adjustments. 20 As shown in Figs. III and IV, the arcuate arm 31 projects outward from the point of its attachment to the eccentric rod 29 within the machine housing through a vertical slot 41 in the side of the post 2a. The eccentric and its rod are thus 25 concealed and protected with provision however for regulation of the rock shaft movement at the exterior.

The operation of the ruffling mechanism is as follows:

30 The two fabric strips concurrently delivered through the folders 13 and 14 are intermittently advanced by the action of the feed dog (not illustrated) of the machine beneath the seaming needle 5, said strips being maintained in separation 35 by the separator plate 15 until they reach a point immediately in advance of the needle. By the action of the ruffler blade which is constantly reciprocated by the swinging movement of the arm 21 on the rock shaft 18, the upper fabric strip 40 is tucked and caught beneath the presser foot 8, the ruffler blade bringing the fabric fold each time slightly beyond the needle. By adjusting the anchorage lug 26 the tension of the spring 25 may be set so as to insure proper action of the 45 ruffler blade for fabrics of different degrees of stiffness. When a change in the size of the tucks in the upper fabric strip is desired, the thumb nut 35 is loosened and the arcuate arm shifted in relation to the head 32 on the rock shaft 18 with the 50 aid of the graduations on said arm. Irrespective of the setting of the arcuate arm 31, the end of the ruffler blade will always be advanced to the same tucking position with respect to the needle 5 by virtue of the specific curvature of said arm 55 predetermined as hereinbefore explained, the adjustments being effective only to vary the outward limit of movement of the blade with corresponding increases in the size of the tucks.

An important advantage obtained by the mechanism thus shown and described is that the eccentric by which it is operated and a part of the arcuate arm are housed in the standard of the machine, so that only enough projects to enable the arcuate arm to be set so that the stroke of the eccentric, which is constant occasions a variable reciprocation of the ruffler blade, the variation however being such that the retreat of the blade is increased or decreased in respect to a substantially fixed forward position of the latter. 60 Thus, notwithstanding changes in the size of the tucks, their forward folds are always brought to the same position with relation to the needle 5 of the sewing machine.

The graduation of the arcuate arm and its visibility and accessibility are important, enabling

the operator to instantly and readily set the device for any predetermined depth of ruffle which may be desired.

Having thus described my invention, I claim:

1. In ruffling mechanism for sewing machines, 5 a reciprocating ruffling blade, means for reciprocating the blade including a rock shaft borne upon the side of the gooseneck of the machine, a head on the rock shaft in which an arcuate slot extends crosswise of the axis of said shaft, an 10 arcuate arm slidably received in said slot and having graduations for coordination with a marker on the head to facilitate setting of the mechanism for determining formation of ruffles of different sizes by the ruffling blade, means for setting the arcuate arm in position in the slot, an eccentric, and an associated strap rod pivotally connected to the end of said arm. 15

2. In a sewing machine having a hollow base and an internally-communicating hollow standard and gooseneck, a needle bar supported for reciprocation in a head at the end of the gooseneck and a ruffling mechanism including a rock shaft extending horizontally along one side of the gooseneck, an arm with a ruffling blade secured to said shaft, a rod extending upward within the vertical standard of the gooseneck from an actuating eccentric, and an arcuate arm to which the rod is pivotally connected at the top, said arcuate arm reaching through an opening at 30 the side of the gooseneck and being slidably adjustable in a head on the rock shaft for the purpose of determining the formation of ruffles of different sizes by the ruffling blade. 35

3. In a sewing machine, a hollow base with an internally communicating hollow standard and gooseneck; and ruffling mechanism including a rock shaft extending horizontally along one side of the gooseneck, an arm with a ruffling blade secured to said shaft, an actuating eccentric with 40 a rod concealed within the hollow of the standard, an arcuate arm to which the end of the eccentric rod is pivotally connected, said arcuate arm reaching outward through an opening in the side of the standard, a head on the rock shaft in 45 which the arcuate arm is slidably engaged, and means accessible at the exterior of the standard whereby the arcuate arm may be secured in adjusted positions relative to the head.

4. In ruffling mechanism for sewing machines, 50 a reciprocating ruffling blade; and means for reciprocating the blade including a rock shaft borne upon the side of the gooseneck of the machine, a head on the rock shaft in which an arcuate slot extends crosswise of the axis of said shaft, an 55 arcuate arm slidably engaged in said slot, means for setting the arcuate arm in position in the slot, an eccentric housed within the frame of the machine, and a strap rod pivoted to the end of the arm, said arm extending through an aperture in 60 the machine frame into engagement with the arcuate slot of the head aforesaid.

5. In ruffling mechanism for sewing machines, a reciprocating ruffling blade; and means for reciprocating the blade including a rotating shaft, 65 an actuating eccentric on said rotating shaft, a strap rod for the eccentric, a rock shaft, an arcuate arm on the rock shaft to which the eccentric strap rod is pivotally connected, said arm having its center of curvature coincident with that of the eccentric when the latter occupies a predetermined position in its rotation; and means whereby the pivotal connection of the eccentric rod 70 can be adjusted toward and away from the axis 75

of the rock shaft to vary the stroke of the ruffling blade.

6. In ruffling mechanism for sewing machines, a reciprocating ruffling blade; and means for reciprocating the blade including a rotating shaft, an actuating eccentric on said rotating shaft, a strap rod associated with the eccentric, a rock shaft, an arcuate arm on the rock shaft to which the eccentric strap rod is pivotally connected, said arm having its center of curvature coincident with that of the eccentric when the ruffling blade is in its fully advanced position relative to the needle of the sewing machine, and means whereby the pivotal connection of the eccentric rod can be adjusted toward or away from the axis of the rock shaft to vary the stroke of the ruffling blade.

7. In ruffling mechanism for sewing machines, a reciprocating ruffling blade; and means for reciprocating the blade including a rotating shaft, an eccentric on said rotating shaft, a strap rod associated with the eccentric, a rock shaft, an arcuate arm slidably engaging a correspondingly configured slot in a head on said rock shaft, said arm having its center of curvature coincident with that of the eccentric when the latter occupies a predetermined position in its rotation, and having a pivotal connection with the eccentric strap rod, and means whereby the arcuate arm may be secured in adjusted positions in the arcuate slot of the head aforesaid to vary the throw of the ruffling blade.
